UNITED STATES PATENT OFFICE.

JOHN GILLIS, OF THE UNITED STATES NAVY.

BELL-BUOY.

1,067,601.

Specification of Letters Patent.

Patented July 15, 1913.

Application filed November 1, 1911, Serial No. 657,940. Renewed June 3, 1913. Serial No. 771,530.

To all whom it may concern:

Be it known that I, JOHN GILLIS, a citizen of the United States, of the United States Navy, at present at Portsmouth, in the county of Rockingham and State of New Hampshire, have invented a new and Improved Bell-Buoy, of which the following is a full, clear, and exact description.

The object of the invention is to provide 10 a new and improved bell buoy, arranged to give desired marine signals when the water is calm or is agitated.

For the purpose mentioned use is made of a buoy carrying a revoluble actuator for the 15 striker of the bell supported on the buoy, and a chain engaging the said actuator for turning it and having one end fixed and the other end provided with a counterweight so that the actuator is turned and the striker 20 actuated according to the movement of the buoy. Use is also made of a pneumatic sounding means periodically actuated by compressed air stored in an air chamber supplied with air from an air compressor 25 actuated through the movement of the buoy.

A practical embodiment of the invention is represented in the accompanying drawings forming a part of this specification, in which similar characters of reference indicate corresponding parts in all the views.

Figure 1 is a sectional elevation of the bell buoy; Fig. 2 is an enlarged cross section of the same on the line 2—2 of Fig. 1; and Fig. 3 is an enlarged sectional elevation of 35 the bell.

The float A of the bell buoy is of the usual size and shape and shackled to an anchor chain B connected with an anchor C held on the bottom of the water-way on which the 40 bell buoy is located. On the top of the float A is erected a suitable framework D supporting at its upper end a hollow tube E on which is fastened the apex of a bell F adapted to be sounded by a striker G and by 45 a pneumatic hammer H, as hereinafter more fully described. The striker G consists of a shank G' pivoted at G² to the tube E, and the free end of the striker G' is provided with a head G³ in which is mounted 50 to slide a stem or a rod G⁴ carrying at its ends balls G⁵, G⁶ adapted to strike against the bell so as to sound the same. The head G³ is provided with a pin G⁷ adapted to be engaged by arms I' of a wheel I secured on 55 a shaft J journaled in suitable bearings arranged on the frame D. The wheel I is pro-

vided with a chain pulley I² over which passes a chain K extending through passageways A' and A² arranged vertically in the float A, one end of the chain K being connected at K' to the anchor C and the other end of the chain supporting a counterweight K², which extends partly in the guideway A² so as to guide the counterweight in its up and down movement.

When the float A sways sidewise by wind or current or rises and falls with the tide, then the chain K imparts a turning motion in one direction or the other to the pulley I² and the wheel I, so that the arms I' thereof engage the pin G⁷ to swing the striker G' to one side and finally release the same so that the striker sounds the bell F. It is understood that when the striker G is swung, say to the left, then the ball G⁶ sounds the bell 75 and the rod G⁴ slides to the right in the head G³ whereby the ball G⁵ is caused to finally sound the bell F on the return movement. When the striker G' is moved from the left to the right then the ball G⁵ first 80 sounds the bell F and the bar G⁴ slides to the left, and on the return movement, after being released by the corresponding arm I', the ball G⁶ strikes the bell F at the other side and again sounds the same. It is understood that the rod G⁴ is usually in an end 85 position so that the striker G' is out of plumb position to insure easy movement of the striker when actuated by the corresponding arms I' of the wheel I.

On the top of the float A and its framework D is mounted an air compressor L, of any approved construction, and connected by an eccentric rod L' and an eccentric L² with the shaft J so that when the latter is 95 turned on turning the wheel I by the action of the chain K, as previously explained, then the air compressor L is actuated to pump air into the float A thus using the latter or a part thereof as an air chamber for storing 100 the compressed air with a view to utilize this compressed air to actuate the pneumatic hammer H. The inlet pipe L³ for the air compressor L extends up through one of the hollow posts of the frame D and terminates 105 in the tube E so that the air inlet pipe is protected by the bell against water, and consequently the air compressor is not liable to be choked with water. The outlet pipe L⁴ of the air compressor L discharges into the 110 float A and the pipes L³ and L⁴ are provided with check valves L⁵, L⁶, and the pipe L³ is

also provided with a drain cup L⁷ for receiving any water that may accidentally get into the pipe L³ and which water is drained out of the pipe prior to reaching the check 5 valve L⁵.

The pneumatic hammer H is of any approved construction and mounted on the frame D in close proximity to the bell F so that when the hammer is actuated it strikes 10 and sounds the bell F. The inlet pipe H' of the pneumatic hammer H is provided with a valve N having a plug N' fixed to the framework D, and the plug N is provided with a port a adapted to register with a U- 15 shaped port b formed in a revoluble member N² mounted to turn on the plug N', the said port b being also adapted to register with a port c formed in the end of the plug N' and connected with a pipe O leading to 20 the interior of the float A or other chamber in which the compressed air is stored. The revoluble member N² of the valve N is provided with a gear wheel N³ in mesh with a gear wheel N⁴ secured on the shaft J, so 25 that when the latter is rotated a rotary motion is given to the valve member N² to alternately connect the ports c and a with each other by way of the port b to permit compressed air to periodically pass from the 30 float A by way of the pipe O and the registering ports c, b, a to the pipe H' and to the pneumatic hammer H to actuate the same and thus sound the bell F. As shown in Fig. 2, the plug N' of the valve N is 35 also provided with another port d adapted to register with the port b on rotating the member N² and this port d is connected by a pipe P with a whistle Q mounted on the float A and sounded by compressed air 40 whenever the port b registers with the ports d and c. It is understood that the ports a, d are preferably arranged diametrically opposite each other so that only one of the ports a or d is in register at the time with 45 the port b.

The float A is provided with a relief valve R to permit escape of excessive pressure in case the float A is charged with compressed air beyond a predetermined pressure.

From the foregoing it will be seen that 50 signals are given by the bell buoy whether the water is calm or is agitated; that is, when the water is agitated the bell is sounded by the striker G and also by the pneumatic hammer H, and the whistle Q is also 55 sounded, but in quieter weather the movement of the float A is not sufficient to cause the wheel I to actuate the striker G, but sufficient turning motion is given to the shaft J 60 to turn the valve N for connecting the pneumatic hammer H or the whistle Q with the compressed air storage chamber to sound either the bell F or the whistle Q.

It is understood that a bell buoy striking 65 above water can be detected port or star-

board, as the case may be, due to the vibrations of the bell being transmitted to the buoy and to the water with very little depreciating effect, and hence the bell buoy will serve as a warning buoy to aid navigation both for transmitting service and submarine signals.

Although I have shown the usual anchoring chain B in connection with the chain K, it is evident that the chain B may be omitted and the chain K used as the anchoring chain on account of being connected with the anchor C.

Having thus described my invention, I claim as new and desire to secure by Letters Patent:

1. A bell buoy provided with an anchored float, a framework on the float, a bell mounted on the framework, a revoluble shaft carrying a pulley and mounted on the said framework, a chain passing over the pulley and fixed at one end, a weight at the other end of the chain, an air compressor driven from the said shaft and discharging into the float, and a pneumatic hammer for sounding the bell and driven by the compressed air in the float.

2. A bell buoy provided with an anchored float, a framework on the float, a bell mounted on the framework, a revoluble shaft carrying a pulley and mounted on the said framework, a chain passing over the pulley and fixed at one end, a weight at the other end of the chain, an air compressor driven from the said shaft and discharging into the float, a pneumatic hammer for sounding the bell, a valve for controlling the said pneumatic hammer and connected with the said float, and means for actuating the said valve from the said shaft.

3. A bell buoy provided with an anchored float, a framework on the float, a bell mounted on the framework, a revoluble shaft carrying a pulley and mounted on the said framework, a chain passing over the pulley and fixed at one end, a weight at the other end of the chain, an air compressor driven from the said shaft and discharging into the float, a pneumatic hammer for sounding the bell, a valve connected with the said float and with the hammer, and means for actuating the said valve from the said shaft.

4. A bell buoy, comprising a float, a bell mounted thereon, an air compressor mounted on the said float, and having an inlet connected with the interior of the bell at the apex thereof, the said air compressor discharging into the said float, means for driving the said air compressor, and pneumatic means for sounding the said bell and driven by compressed air from the said float.

5. A bell buoy, comprising a float, an air compressor mounted on the said float and discharging into the same, driving means actuated by the movement of the float and

connected with the said air compressor to drive the same, a sounding device mounted on said float, and a valve actuated by the driving means for controlling the passage of 5 air from the said float to the sounding device.

6. A bell buoy, provided with a float, a framework on the float, a driving shaft mounted to turn on the said framework, 10 means for actuating the driving shaft by the movement of the float, an air compressor driven from the said shaft and discharging into the float, a sounding means on the float, a valve connected with the said float and 15 with the sounding means, and means for actuating the said valve from the said shaft.

7. A bell buoy, comprising a float, driving means actuated by the movement of the float, an air compressor driven by the said driving 20 means, a sounding device mounted on the float, means for storing the compressed air, and means actuated from the said driving means for periodically controlling the flow of the compressed air to the said sounding 25 means.

8. A bell buoy, comprising an anchored float, a bell mounted thereon, driving means actuated by the movement of the float, an air compressor driven by the said driving

means, a compressed air chamber into which 30 discharges the said air compressor, a pneumatic sounding means connected with the said chamber for sounding the said bell, and controlling means actuated from the said driving means and periodically controlling 35 the flow of compressed air from the said chamber to the said sounding means.

9. A bell buoy, comprising a float, a sounding device mounted thereon, a shaft mounted to turn, means actuated by the movement 40 of the float for driving said shaft, an air compressor, means for actuating the air compressor from said shaft, the said air compressor discharging into the interior of the float, a passage connecting the said float 45 with the sounding device, a valve having a revoluble member for controlling the passage of air from the float to the sounding device, and means for driving the revoluble member of the valve from said shaft. 50

In testimony whereof I have signed my name to this specification in the presence of two subscribing witnesses.

JOHN GILLIS.
